BASS DRUM STAND

Gordon C. Allen, Detroit, Mich.

Application November 23, 1955, Serial No. 39,027

Term of patent 14 years

(Cl. D56—1)

Fig. 1 is a side elevational view of a bass drum stand embodying my design.

Fig. 2 is a front elevational view thereof.

Fig. 3 is a rear elevational view thereof.

Fig. 4 is a top plan view thereof.

The conventional chair and snare drum shown in dotted lines are for illustrative purposes.

I claim:

The ornamental design for a bass drum stand, as shown and described.
